HOOD LOCK

Filed Feb. 24, 1931

Fig. 1.

Fig. 2.

Inventor:
John C Ellison.

UNITED STATES PATENT OFFICE

JOHN C. ELLISON, OF CHICAGO, ILLINOIS.

HOOD LOCK

Application filed February 24, 1931. Serial No. 517,815.

The invention relates to a hood lock of the type more particularly for use on automobiles to securely hold the hood of the car in closed position.

5 The present day cars as manufactured are provided with hood clamps for holding the hood closed but not of the type that may be locked to render it impossible for anyone not authorized to do so, to tamper with any of the parts under the hood.

An object of my invention is to construct a hood lock that is simple in construction, effective in operation, of few parts and inexpensive to manufacture.

15 Another object is to provide a hood lock comprising two members, one being permanently secured to the frame of a car, and the other member secured near the lower edge of the hood of the car, so that when the hood is closed, the member secured to the frame may be positively and securely locked to the removable member, thereby rendering it impossible to open the hood without the use of a key.

20 With the foregoing and other objects in view, which will appear as the description proceeds, the invention resides in the combination and arrangements of parts and in the details of construction hereinafter described and claimed, it being understood that changes in the precise embodiment of the invention herein disclosed can be made without departing from the spirit of the invention.

25 In the accompanying drawing:

Fig. 1 is a side elevation illustrating my device as attached to the frame and hood of an automobile.

30 Fig. 2 is a view similar to Fig. 1 showing the body of the device in section; Fig. 3 is a side elevation of the device taken on line 3—3 of Fig. 1; Fig. 4 is a vertical sectional view on line 4—4 of Fig. 1. Fig. 5 is a detail sectional view of a modified form of arm.

35 Referring to the drawing, the numeral 10 designates the body or base, provided with the flanges 11—11 adapted to be secured to the frame or hood plate 12. The body of the device is provided with an opening 13 extending vertically and reduced at the upper

end to provide an opening 14. On opposite sides the body 10 is provided with elongated openings 15—15, while the front and rear portion are provided with vertical slot openings 16—16.

40 A pair of oppositely disposed arms or grippers 17—17 are pivoted on a short shaft 18 which is guided and slidably mounted in the vertical slot openings 16—16 and extend through the openings 15—15 of the body 10 and are yieldingly held at the bottom of the slots 16—16 by a headed plunger 19 slidably mounted in the opening 14 and held in yielding contact against the arms 17—17 by means of a compression spring 20 interposed between the head of the plunger 19 and the top wall of the body 10.

45 The arms or grippers 17—17 are pivoted side by side on the shaft 18 and are each provided with a hole or opening 21 spaced some distance below the shaft 18, through which a pin or plunger 22 of a lock 23 extends when the openings register. The lock 23 is threaded or otherwise secured in the body 10.

50 Each arm 17 is provided at its upper end with an inwardly extending portion 17—a and an outwardly extending finger piece 17—b. The inwardly extending portions 17—a of the arms 17 are adapted to engage a substantially channel shaped member 25 secured to the hood 26 of a car, so that when the hood is closed the channel shaped member 25 will be brought into the path of the arms 17—17 and spaced some distance from the top of the body member 10.

55 Assuming the arms 17—17 to be in the position shown in dotted lines in Fig. 2, the operator takes hold of the finger pieces 17—b and lifts up, and in so doing the plunger 19 compresses the spring 20 so that when the arm is released, the projection 17—a will be held in yielding contact with the channel member 25. A flattened portion 27 is provided on the arms 17 just above their pivotal point 18 and is engaged by the headed plunger 19 to retain the arms 17—17 in an upright position.

60 The holes 21—21 in the arms 17 are below the pivotal point and when the arms are in the position shown in full lines Fig. 2, the

plunger 22 of the lock 23 is projected into them to hold the arms permanently locked to the removable member 25.

On the member 25 I provide the lugs or 5 projections 28 adapted to engage and fit into the recesses 29 to insure perfect alinement of the arms 17-17 so that the openings in the arms will register and the plunger 22 of the lock 23 will be easily projected into the 10 openings 21-21 to lock the arms.

10 In Fig. 5 which illustrates a modified form of arm, I provide an inclined surface 30 on the hook or arm 17' so that the removable member 25' may be dropped into position 15 and held by the arms under the tension of the spring as above described.

I claim:

1. A device of the character described, comprising in combination a body member, 20 a pair of oppositely-disposed arms pivotally mounted in the body member, spring tension means coacting with said arms for yieldingly holding them in open and closed position, a removable member adapted to be held by said 25 arms and a lock in the body member to engage the arms to securely hold them while they are engaged with the removable member.

2. A hood clamp comprising in combination a base portion adapted to be secured to 30 the frame of a car, a substantially channel shaped member secured to the lower edge of the hood of the car, a pair of oppositely disposed hooks pivotally mounted in said base portion adapted to engage the channel shaped 35 member, a spring pressed plunger engaging each of said hooks near their pivotal point and a plunger lock fixed in the base portion adapted to engage each of said hook members adjacent their pivotal point.

40 3. A hook clamp comprising in combination a hollow body portion, having a base adapted to be secured to the frame of a car, a substantially channel shaped member secured to the hood of the car, a pair of upwardly extending arms provided with inwardly extending projections, said arms being pivotally mounted in vertical elongated slots and provided with a flattened portion 45 above its pivot, a spring pressed plunger engaging the flattened portion of said arms to normally hold them in upright position to engage each edge of said channel shaped member and a lock adapted to engage both arms to securely hold them in their upright 55 position.

4. A hood lock of the character described, comprising in combination a base portion, said base portion having side walls provided with openings therein, a front wall, a rear wall, said front and rear walls having alined vertical elongated slots, a top wall integral with front and rear walls and said side walls, a pair of upwardly extending gripping members, pivotally mounted in said elongated 60 slots extending through the openings in the

65 said walls and provided with inwardly extending portions at their upper extremities adapted to engage a relatively short plate, a spring pressed plunger engaging each of 70 said gripping members near their pivotal point to yieldingly hold them in the elongated slots, finger pieces extending outwardly adjacent the inwardly extending portions and a keylock provided with a plunger adapted to engage the gripping members below their 75 pivotal point.

5. A hood lock of the character described, comprising in combination, a hollow body member having openings in the sides thereof and elongated slots disposed in alined relation in the front and back thereof, a pair of arms pivotally mounted in the elongated slots, a spring tension exerting a presser on each arm at their pivotal center to normally hold the arms yieldingly at the lower end of the 80 elongated slot, said arms being provided with inwardly extending projections at their upper ends adapted to engage a removable member and lock means adapted to engage and permanently hold the arms in upright position 85 while engaged with the removable member.

6. A device of the character described, comprising in combination a body member, a pair of arms pivotally and yieldingly mounted in the body member, spring means for yieldingly holding the arms in upright position, said 90 arms having inwardly extending portions at the upper end thereof, a removable member adapted to be positioned between said arms, under the inwardly extending portions and a lock in the body member adapted to engage both arms while the arms are normally upright.

In testimony whereof I have signed this specification.

JOHN C. ELLISON.
